ABSTRACT: A safety throttle control for an internal combustion engine utilizes a liquid pressure expandable link in the fuel control pedal coupling to the engine, and flow couples the lubrication system of the engine to the liquid pressure expandable link, whereby the fuel control pedal becomes functional only when lubrication pressure exists.

SAFETY THROTTLE CONTROL

My invention relates to engines such as internal combustion engines, and more particularly to a safety throttle control for such an engine.

Engines such as internal combustion engines have built-in lubrication systems, wherein lubrication is accomplished under pump pressure during operation of the engine. Should such lubrication fail, from whatever cause, such as failure of the oil pump, or development of leakage in the system, it is no longer safe to operate such engine, especially under load, for the failure of lubrication will result in burning out of bearings and other damage to the engine, necessitating costly repairs with resulting costly downtime.

This problem has long been recognized, and attempts at a solution thereof have been in the direction of signaling the operator upon failure of lubrication. However, should the operator fail to notice the danger signal, or neglects to heed it, the signal has not accomplished its ultimate purpose, and the engine will fail, the same as if no signal system were provided.

Among the objects of my invention are;

1. To provide a novel and improved safety throttle control for an internal combustion engine;
2. To provide a novel and improved safety throttle control for an internal combustion engine, which can function only in the presence of lubrication pressure; and
3. To provide a novel and improved safety throttle control for an internal combustion engine, which control can become functional only in the presence of lubrication pressure in the engine.

Additional objects of my invention will be brought out in the following description of a preferred embodiment of the same, taken in conjunction with the accompanying drawings, wherein

FIG. 1 is an outline view of an internal combustion engine, and depicting the application of the present invention thereto; and

FIG. 2 is a view in section, taken in the plane 2-2 of FIG. 1.

Referring to the drawings for details of my invention in its preferred form, the invention is shown installed in an engine 1 of the internal combustion type having a fuel pump 3 with a control lever 5 mounted externally thereof, the movement of which will control fuel delivery to the engine. Normally, this lever is controlled by the driver through a conveniently located foot pedal 7 which is connected to the fuel-controlled lever by a connection which is wholly mechanical.

In accordance with the present invention, I introduce into the connection between the foot pedal and the fuel pump lever, an hydraulic link 9 supplied by oil from the lubrication system of the engine, and under the prevailing pressure of the oil in such system.

The hydraulic link in the preferred form of my invention, may take the form of a cylinder 13 having a cap 15 at one end, while at its other end, it is closed by a fitting 17 having a threaded opening 19 for coupling thereto, of a suitable flow connection 21 from any convenient location 20 in the lubrication system of the engine.

Within the cylinder is a piston 21 slidably sealed therein by an O-ring 23 installed in a groove 25 about the piston.

The piston is provided with a piston rod 27 slidably passing through the cap 15 and terminating externally of the cylinder, in a threaded end 29. Installed within the cylinder, between the piston and the cap is a biasing compression spring 31 normally urging the piston toward the fitting end of the cylinder.

Such hydraulic link is installed in the connection between the foot pedal 7 and the fuel pump lever 5 by providing the fitting 17 with a suitable threaded end recess 33 for connection thereto of an eye bolt 35, which enables coupling of this end of the hydraulic link to the fuel pump lever 5 by way of a small intermediate link 37, hingedly coupling the eyebolt to the end of the lever. The threaded end of the piston rod, in turn, may be threadedly secured to an end of a rod 39 extending to the foot pedal 7 to which it is hingedly secured.

The oil line connection 21 places the hydraulic link 9 in flow communication with the lubrication system of the engine, and thus, oil from the lubrication system has free access to the cylinder of the hydraulic link.

5 In the absence of pressure in the lubrication system, as may occur when the engine is not running, the piston 21 will be urged by the biasing spring 31 toward the fitting end of the cylinder, to the extent permitted by the foot pedal when such pedal is at its lowest permissible position.

10 Upon starting the engine, the resulting buildup of pressure in the lubrication system, will bring about an inflow of oil into the cylinder under pressure, which will drive the piston back against the prevailing spring pressure and urge the foot pedal to its uppermost position, which it will occupy during idling of the engine.

15 The presence in the hydraulic link, of oil under pressure, imparts to the hydraulic link, the characteristics of a solid or mechanical link, and so long as such pressure exists, the application of foot pressure to the foot pedal, to manipulate or control fuel to the engine, will have the same effect as if a solid mechanical link existed at this point, and the operator will not be cognizant of any difference, so long as the hydraulic pressure existed in the hydraulic link.

20 However, should the oil pressure in the lubrication system of the engine, for some reason or other, fail, the hydraulic link will lose its pressure and will collapse and become nonfunctional, thus permitting movement of the piston under the action of the biasing spring, with a resulting collapse of the foot pedal to its lowest permissible position. It thereafter becomes impossible to exercise continued control over the fuel supply to the engine, and with such loss of control, the engine can do nothing but idle, and the truck in which the engine is installed, can no longer be driven until the failure in the lubrication system has been cured.

25 FIG. 1 is an outline view of an internal combustion engine, and depicting the application of the present invention thereto; and

30 While the invention in its preferred form, has been illustrated and described in conjunction with an engine of the internal combustion type, it is just as applicable to any type engine having a lubrication system.

35 From the foregoing description of my invention in its preferred form it will be apparent that the same fulfills all the objects of my invention, and while I have illustrated and described the same in considerable detail and in its preferred form, the same is subject to alteration and modification without departing from the underlying principles involved and I accordingly do not desire to be limited in my protection to these specific details illustrated and described except as may be necessitated by the appended claims.

I claim:

40 1. A safety throttle control for an engine having a pressure lubrication system and means for supplying fuel to said engine, said safety throttle control comprising a fuel control pedal, a hydraulic link comprising a cylinder component and a piston component slidably installed in said cylinder component, means for operatively connecting one of said hydraulic link components to said pedal, means for operatively connecting the other of said hydraulic link components to said fuel-supplying means, and means for flow coupling said pressure lubrication system to said cylinder component to permit direct manipulation of said fuel supplying means from said pedal through said hydraulic link while said cylinder is receiving oil under pressure from said lubrication system.

45 2. A safety throttle control in accordance with claim 1, characterized by said means for operatively connecting one of said hydraulic link components to said pedal comprising a rod connected to said piston component.

50 3. A safety throttle control in accordance with claim 2, characterized by said means for operatively connecting the other of said hydraulic link components to said fuel supplying means, comprising said cylinder component including a fitting at one end having a flow passageway therethrough into said cylinder component, and said means for flow coupling said lubrication system to said cylinder component, including a flow line connected to said fitting at one end of said passageway.

55 75

4. A safety throttle in accordance with claim 2, characterized by a compression spring in said cylinder component between said piston component and the proximate end of said

4 cylinder component and adapted to be compressed upon admission of oil under pressure into said cylinder component.
